US00D802898S

(12) **United States Design Patent** (10) Patent No.: **US D802,898 S**
Montross et al. (45) Date of Patent: ** Nov. 21, 2017

(54) **SHOE**(71) Applicant: **Reebok International Limited**, London (GB)(72) Inventors: **Matthew Montross**, Middleboro, MA (US); **Ricardo Vestuti**, Providence, RI (US)(73) Assignee: **Reebok International Limited**, London (GB)(**) Term: **15 Years**(21) Appl. No.: **29/546,332**(22) Filed: **Nov. 20, 2015****Related U.S. Application Data**

(60) Division of application No. 29/470,560, filed on Oct. 22, 2013, now Pat. No. Des. 745,256, which is a division of application No. 29/444,897, filed on Feb. 5, 2013, now Pat. No. Des. 693,551, which is a continuation-in-part of application No. 13/545,603, filed on Jul. 10, 2012.

(51) **LOC (10) Cl.** ..... **02-04**(52) **U.S. Cl.**USPC ..... **D2/954**; D2/947; D2/951(58) **Field of Classification Search**

USPC ..... D2/902, 906, 908, 916, 918, 925, D2/946-962, 977; 36/3 B, 22 R, 24.5, 36/25 R, 28, 32 R, 34 R, 59 C, 67 A, 103

“KICKSstyle” in The International Street Magazine. pp. 54-55, Aug. 20, 2001 (with. translation of p. 55).

Primary Examiner — T. Chase Nelson

(74) *Attorney, Agent, or Firm* — Sterne, Kessler, Goldstein & Fox PLLC.

(57) **CLAIM**

The ornamental design for a shoe, as shown and described.

DESCRIPTION

FIG. 1 is a top perspective view of a shoe showing our new design;

FIG. 2 is a side view thereof;

FIG. 3 is another side view thereof;

FIG. 4 is a bottom view thereof;

FIG. 5 is a front view thereof; and,

FIG. 6 is a rear view thereof.

The broken lines in the Figures show environment for illustrative purposes only and form no part of the claimed design.

1 Claim, 5 Drawing Sheets# US D802,898 S
